CLAIM

The ornamental design for a game console, as shown and described.

DESCRIPTION

FIG. 1 is a front perspective view of a game console, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top perspective view thereof in a folded state; and,

FIG. 10 is an enlarged detail view of area 10 in FIG. 2.

The evenly spaced broken lines in the drawings illustrate portions of the game console that form no part of the claimed design. The dot-dash-dash broken lines indicating an enlargement portion of the design form no part of the claimed design.

1 Claim, 10 Drawing Sheets
